UNITED STATES PATENT OFFICE

JOHN G. ROSSITER, OF JACKSON, MICHIGAN, ASSIGNOR TO REYNOLDS SPRING COMPANY,
OF JACKSON, MICHIGAN, A CORPORATION OF DELAWARE

DESIGN FOR A CONDIMENTS DISPENSER

Application filed August 8, 1932. Serial No. 44,542. Term of patent 7 years.

To all whom it may concern:

Be it known that I, JOHN G. ROSSITER, a citizen of the United States, residing at Jackson, in the county of Jackson and State of Michigan, have invented a new, original, and ornamental Design for Condiment Dispensers, of which the following is a specification, reference being had to the accompanying drawing, forming part thereof.

Fig. 1 is a side elevation of the dispenser.

Fig. 2 is a plan view of Fig. 1, taken as designated by the arrows 2—2.

Fig. 3 is a bottom view of Fig. 1, taken as designated by the arrows 3—3.

Fig. 4 is a cross sectional view taken as designated by the arrows 4—4.

I claim:

The ornamental design for a condiment dispenser as shown.

JOHN G. ROSSITER.
